United States Patent

Des. 242,551
Patented Nov. 30, 1976

242,551

TELEPHONE DIAL INSERT

George W. Upham, 7 Frederick Circle, Lynn, Mass.
01904, and Walter E. Steele, 87 Parkside Ave., Braintree, Mass. 02184

Filed Apr. 14, 1975, Ser. No. 567,541

Term of patent 14 years

Int. Cl. D14—03

U.S. Cl. D26—14 A

FIG. 1

FIG. 2

FIG. 3

FIG. 4

FIG. 1 is a perspective view of a telephone dial insert showing our new design.

FIG. 2 is a side elevation view thereof; in an enlargement relative to its illustration in FIG. 1;

FIG. 3 is a top plan view of the insert of FIG. 2; and

FIG. 4 is a bottom view thereof.

The structure shown in broken line work is not part of our new design, but indicates an environmental association of the claimed design.

We claim:

The ornamental design for a telephone dial insert, substantially as shown and described.
